WITNESS:

Chas. L. Giesbauer

By

UNITED STATES PATENT OFFICE.

ROBERT D. PRYDE, OF ORANGE, CONNECTICUT.

GOLF TEE.

Application filed April 25, 1924. Serial No. 708,944.

To all whom it may concern:

Be it known that I, ROBERT D. PRYDE, a citizen of the United States, residing at Orange, in the county of New Haven and

5 State of Connecticut, have invented certain new and useful Improvements in Golf Tees, of which the following is a specification, reference being had therein to the accompanying drawings.

10 This invention relates to a new and improved golf tee.

It is the object thereof, among other things, to provide a reusable tee that may be readily positioned and will provide a firm 15 and rigid seat for the golf ball, will have the maximum rigidity and strength with the minimum possibility of injury thereto, and designed so that dirt or other foreign substances will not interfere with its efficiency.

20 In the drawings, wherein like numerals of reference designate like parts in the several figures:

Figure 1 is an elevation of my improved 25 golf tee, illustrated as being positioned in the ground with a golf ball poised thereon;

Figure 2 is a plan view thereof; and

Figure 3 is an enlarged longitudinal sectional view thereof.

30 My improved golf tee, which is designated 10, is preferably conical in form, having a cavity or pocket 11 in the larger end thereof, and an adjacent end face 12 shown herein as inclining downwardly from the outer 35 edge of the tee.

While I have illustrated the face 12 as inclined downwardly toward the cavity or pocket 11, it may be made flat if desired, or inclined downwardly away from the cavity 40 or pocket, or the latter may at its outer end be substantially the same diameter as the larger end of the tee, in which case there would be no end face.

45 The cavity or pocket 11 is also most usefully employed in nesting the tees in the carton or the like.

This tee is positioned by pressing the same into the ground to the desired depth, as shown in Figure 1, and owing to its strong structure, will not break or be injured thereby, and after rendering service 50 is removed for subsequent use.

The golf ball 13, when positioned, finds a firm and rigid seat on the end face 12 with a portion of its periphery projecting into 55 the cavity or pocket 11.

In re-usable tees heretofore made the slightest accumulation of dirt on the top of the tee forms an obstruction for the ball and prevents the same acquiring a good seat 60 thereon. If this dirt is not discovered until after the tee is positioned the task of cleaning it is a most inconvenient one.

With my improved tee a limited amount of dirt or other foreign substance can accumulate in the bottom of the cavity or pocket 11 without affecting the efficiency of the tee and can be removed with the slightest inconvenience.

What I claim as new and desire to secure 70 by Letters Patent, is:—

1. A re-usable golf tee, having a cavity or pocket in one end thereof, and a downwardly flaring face upon the end thereof between the pocket and the periphery of the 75 tee.

2. A re-usable golf tee, conical in form, with a cavity or pocket in the larger end thereof of less diameter than said end, and that portion of such end between the cavity 80 or pocket and outside edge forming a seat for the ball.

3. A re-usable golf tee, conical in form, with a cavity or pocket in the larger end thereof of less diameter than said end, and that portion of such end between the cavity 85 or pocket and outside edge forming a seat for the ball that inclines downwardly from the outside edge to the cavity or pocket.

In testimony whereof, I have hereunto 90 affixed my signature.

ROBERT D. PRYDE.
